UNITED STATES PATENT OFFICE

149,335

DESIGN FOR A COMBINATION DESK UNIT

Charles H. Beatty, Philadelphia, Pa.

Application July 24, 1946, Serial No. 131,871

Term of patent 7 years

(Cl. D74—1)

To all whom it may concern:

Be it known that I, Charles H. Beatty, a citizen of the United States, residing in Philadelphia, county of Philadelphia, Commonwealth of Pennsylvania, have invented a new, original, and ornamental Design for a Combination Desk Unit, of which the following is a specification, reference being had to the accompanying drawing, which forms a part thereof.

The figure is a front perspective view of a combination desk unit showing the essential features of my design in full lines, the printed matter being merely representative of that which would appear from time to time.

I claim:

The ornamental design for a combination desk unit substantially as shown and described.

CHARLES H. BEATTY.
